ROTATABLE TRIGGER GUARD FOR FIREARMS

Cyril A. Moore, Springfield, Mass., assignor to the United States of America as represented by the Secretary of War

Application May 5, 1949, Serial No. 91,619

3 Claims. (Cl. 42—69)

(Granted under the act of March 3, 1883, as amended April 30, 1928; 370 O. G. 757)

1

The invention described in the specification and claims may be used by or for the Government for governmental purposes without the payment of any royalty thereon.

This invention relates to a trigger guard for a firearm and more particularly to a collapsible type of construction wherein the guard can be rotated laterally out of the vertical plane of trigger movement.

The wearing of heavy fingerless mittens in extreme cold weather introduces considerable difficulty in the operation of those firearms which have conventional fixed type trigger guards. In resorting to the obvious solution of increasing the size of the guard, it has been found that the protection against accidental pulling of the trigger has been significantly decreased. On the other hand, the use of auxiliary trigger attachments connected to the trigger invariably requires additional parts or at best repositioning of existing parts. As a result, the optimum of gun design can not be satisfactorily achieved.

Accordingly, it is an object of this invention to provide a firearm with a novel trigger guard capable of 90 degree lateral rotation about either side of a conventional trigger protecting position.

The specific nature of the invention as well as other objects and advantages thereof will clearly appear from a description of a preferred embodiment as shown in the accompany drawings in which:

Fig. 1 is a side elevational view partly in cross-section showing the trigger guard construction of this invention.

Fig. 2 is a front end view showing the trigger guard in one of its rotated positions.

Fig. 3 is a side view of the locking arrangement in the disengaged position.

Fig. 4 is a front view of the locking member.

Fig. 5 is a fragmentary view showing that portion of the trigger guard which is arranged to be secured by the locking member of Fig. 4.

Fig. 6 is a front view of the front trigger guard bracket.

Fig. 7 is a side elevational view of an alternate method of securing the trigger guard in its conventional trigger protecting position.

Fig. 8 is a front elevational view showing in more detail the locking arrangement of Fig. 7.

There is illustrated in Fig. 1 a trigger guard 5 of conventional contour, a trigger 6, and a channel-shaped trigger plate 7 arranged to be suitably secured to the underside of a firearm (not shown). A rectangular slot 10 is provided in

2

plate 7 and the finger engaging portion of trigger 6 extends therethrough. Right angled brackets 8 and 9 are suitably secured to the bottom of trigger plate 7 and lie in opposed relationship.

Trigger guard 5 is rotatably secured between brackets 8 and 9 by means of a pin 11 at the rear end and a lock member 12 at the front end. Lock 12 consists of a head portion 13 and a pin-like shank 14 having a D-shaped cross-section arranged to extend through a hole 24 in the front end of trigger guard 5 and through a hole 25 in front bracket 8. Hole 25 is also D-shaped as shown in Fig. 6 and consequently lock member 12 is thereby prevented from rotating in front bracket 8. The free end of shank 14 is threaded to receive a cap 15 which is counterbored as shown at 16. A coil spring 17 is arranged to surround shank 14 and be compressed between the front face of front bracket 8 and the shoulders formed by counterbore 16. The front end of trigger guard 5 is enlarged as shown at 26 in Fig. 5 to correspond with the contour of head 13 of lock member 12 and is provided with a plurality of diametrically aligned holes 19 arranged to mate with a pair of diametrically opposed studs 18 on the inner face of head 13 when the parts are assembled as shown in Figs. 1 and 2. The bias of spring 17 maintains studs 18 in engagement with holes 19.

When it is desired to rotate trigger guard 5 out of its conventional trigger protecting position, it is merely necessary to pull or push lock member 12 rearwardly and sufficiently to disengage studs 18 from holes 19 and then rotate trigger guard 5 laterally with respect to the longitudinal axis of trigger plate 7. When holes 19 no longer align with studs 18, lock member 13 may be released. When holes 19 are once again aligned with studs 18, the bias of spring 17 automatically effects engagement and thereby locks trigger guard 5 in a trigger exposing position. During rotation of trigger guard 5, the engagement of shank 14 with hole 25 as described above prevents rotation of lock member 13.

An alternate method of locking a trigger guard 23 in any of its aforementioned positions is illustrated in Figs. 7 and 8. Although one end only of trigger guard 23 is shown in the drawing, it is to be understood that the construction about to be described applies equally to the other end. Bracket 27 is similar in all respects to the previously mentioned brackets 8 and 9 except that intersecting grooves 20 are cut into the outer face of the downwardly extending section. Trigger guard 23 is here rotatably secured to

bracket 27 by a pin 21. A flat spring 22 having a projecting detent 23 formed at the upper end thereof is secured to the upstanding portion of trigger guard 28 as by riveting. Detent 23 is thereby arranged to normally engage in one of grooves 20. However, when trigger guard 28 is rotated from a trigger protecting position to a trigger exposing position, or vice versa, detent 23 is forced out of vertical groove 20 until a position is reached where it engages one of the horizontal grooves 20. Thereupon, the resiliency of flat spring 22 biases detent 23 into engagement with groove 20 and trigger guard 28 is thus secured in any of the positions corresponding to the locations of grooves 20. Again, although here shown as two grooves intersecting at right angles, it is within the intent of this invention to provide a plurality of grooves intersecting at various angles so that the trigger guard may be secured in any position within a 180 degree arc of rotation.

Thus, there is here provided a simple yet positive means for rotating a trigger guard out of the way of a trigger so that such trigger may be easily manipulated by an operator wearing heavy fingerless mittens. The construction of the parts is such that inexpensive methods of manufacture, such as stamping, may be readily employed.

I claim:

1. In a trigger guard construction for firearms, a trigger guard having upstanding opposite ends, one of said ends having a plurality of radially disposed holes, means including a locking member for selectively securing said trigger guard to the firearm in one of a plurality of laterally rotated positions, said locking member having at least one projecting stud, resilient means operative on said locking member for urging engagement of said stud in one of said trigger guard holes, and means for preventing rotation of said locking member when said trigger guard is rotated laterally with respect to the longitudinal axis of the firearm.

2. In a trigger guard construction for firearms, a trigger guard having upstanding opposite ends, one of said ends having a plurality of diametrically opposed holes, a pair of opposed right angle brackets fixedly secured to the underside of the firearm, one of said brackets having a D-shaped hole in the downwardly extending portion there-

10

20

of, means including a locking member for releasably securing said trigger guard between said brackets, said locking member having a head portion and a shank portion of D-shaped cross-section, a pair of projecting studs on said locking member head portion, a cap threadably secured to the free end of said shank portion, and resilient means in said cap member arranged to bias said lock member whereby said projecting studs engage with said trigger guard holes when aligned therewith, said locking member shank portion cooperating with said bracket D-shaped hole to prevent rotation of said locking member when said trigger guard is rotated laterally with respect to the longitudinal axis of the firearm.

3. In a trigger guard construction for firearms, a pair of brackets fixedly secured at one end thereof to the firearm, each of said brackets having a downwardly extending portion in opposed relationship to one another, a trigger guard having opposite upstanding end portions releasably secured between said downwardly extending bracket portions, said trigger guard being thereby mounted for lateral rotation with respect to the longitudinal axis of the firearm, each of said downwardly extending bracket portions having a plurality of grooves on the exposed face thereof radially disposed to define an arc of at least 180°, a flat spring fixedly secured to said upstanding end portions of said trigger guard, and detent means on each of said flat springs arranged for engagement with one of said bracket grooves when aligned therewith, all adapted and arranged whereby said trigger guard is releasably retained in a position corresponding to the location of said particular groove engaged by said detent.
